UNITED STATES PATENT OFFICE.

OLAF S. STROM, OF LOS ANGELES, CALIFORNIA.

DESIGN FOR AN ELECTROLIER.

43,972.

Specification for Design.

Patented May 6, 1913.

Application filed February 25, 1913. Serial No. 750,699. Term of patent 3½ years.

To all whom it may concern:

Be it known that I, OLAF S. STROM, a citizen of the United States, residing at Los Angeles, in the county of Los Angeles and State of California, have invented a new, original, and ornamental Design for Electroliers, of which the following is a specification, reference being had to the accompanying drawing, forming part thereof.

Figure 1 is a side elevation of my lighting

fixture. Fig. 2 is a half plan view of that portion of the lighting fixture in which the electric lamps are mounted.

I claim:

The ornamental design for an electrolier as shown.
